Primary Examiner—Alan P. Douglas*Assistant Examiner*—Antoine D. Davis[57] **CLAIM**

The ornamental design for a fluorescent lamp crusher,
as shown and described.

DESCRIPTION

FIG. 1 is a front assembly view of the fluorescent lamp crusher showing my new design;

FIG. 2 is a rear assembly view thereof;

FIG. 3 is a left side assembly view thereof;

FIG. 4 is a right side assembly view thereof;

FIG. 5 is a top plan view thereof; and,

FIG. 6 is a bottom plan view thereof.

Portions of the cord element have been omitted from
the drawing for ease of illustration.

FIG. 1

FIG. 2

FIG. 3

FIG. 4

FIG. 5

FIG. 6
